UNITED STATES PATENT OFFICE

162,062

VANITY CABINET

Nello J. Orsini, Royal Oak, Mich.

Application July 18, 1950, Serial No. 11,247

Term of patent 14 years

(Cl. D33—19)

To all whom it may concern:

Be it known that I, Nello J. Orsini, a citizen of the United States, residing at Royal Oak, in the county of Oakland and State of Michigan, have invented a new, original, and ornamental Design for a Vanity Cabinet, of which the following is a specification, reference being had to the accompanying drawings, forming a part thereof.

I claim:

The ornamental design for a vanity cabinet, as shown.

NELLO J. ORSINI.
